US00D652741S

(12) **United States Design Patent**
Van Scoyoc et al.

(10) **Patent No.:** **US D652,741 S**
(45) **Date of Patent:** **** Jan. 24, 2012**

(54) **CONTAINER**

(75) Inventors: **Velissa Van Scoyoc**, Pottstown, PA (US);
Robert Ziegler, E Windsor, NJ (US);
Sean Rich, Hamilton, NJ (US)

(73) Assignee: **Silgan Containers LLC**, Woodland Hills, CA (US)

(57) **CLAIM**

We claim the ornamental design for a container, as shown and described.

DESCRIPTION

FIG. 1 is a perspective view of a container showing our new design;

FIG. 2 is a front view thereof, with the rear view being the same;

FIG. 3 is a left side view thereof, with the right side view being the same;

FIG. 4 is a top view thereof; and,

FIG. 5 is a bottom view thereof.

The broken lines in the drawings show unclaimed subject matter only and form no part of the claimed design.

1 Claim, 4 Drawing Sheets
